Primary Examiner — Paul D Bohannon(74) *Attorney, Agent, or Firm* — Banner & Witcoff, Ltd.**CLAIM**

The ornamental design for a chair, as shown and described.

DESCRIPTION

FIG. 1 is a top, front, left perspective view of the claimed design for a chair;

FIG. 2 is a front view thereof;

FIG. 3 is a right view thereof; and,

FIG. 4 is a left view thereof.

The broken lines immediately adjacent to the shaded area depict boundaries of the claimed design and form no part thereof. The broken lines showing the remainder of the chair depict environmental structure and form no part of the claimed design.
